UNITED STATES PATENT OFFICE

2,663,453

FLOATING ROOF FOR SEWAGE DIGESTING APPARATUS

John H. Wiggins and John W. Allen, Chicago, Ill.;
said Allen assignor to said Wiggins

Application August 31, 1950, Serial No. 182,444

4 Claims. (Cl. 220—26)

1

This application is a continuation-in-part of our joint application for patent Serial No. 123,762, filed October 26, 1949, for Sewage Digesting Apparatus, which resulted in U. S. Patent 2,605,014, dated July 29, 1952.

Our said application discloses a sewage digesting apparatus, whose floating cover comprises a gas collecting chamber, a flexible deck portion extending radially from said gas collecting chamber, and an annular-shaped load member formed from a relatively heavy, moldable material attached to the peripheral edge of said flexible deck portion so as to maintain same in such a position as to induce the flow of gases on the underside of said cover, into said gas collecting chamber.

The main object of our present invention is to reduce the amount of metal used in the peripheral portion of a floating cover for sewage disposal apparatus, that embodies the basic idea of the floating cover disclosed in our above mentioned pending application for patent.

Another object is to reduce the cost and simplify the operation of building such a floating cover.

The figure of the drawing is a fragmentary, vertical, transverse sectional view of a floating cover embodying one form of our present invention.

In the drawings, the reference character A designates the side wall of the tank of the apparatus that holds the sewage or other liquid being processed, B designates the gas collecting chamber at the center of the floating cover that is adapted to receive gases evolved from the sewage, C designates the flexible deck portion of the cover that extends radially from said gas collecting chamber, and D designates the annular-shaped load member, made of concrete or other moldable material, that is attached to the periphery of said deck portion C, so as to maintain the same in an inclined position, sloping upwardly from its outer edge towards the center of the cover, and thus induce a flow of gases on the underside of the cover into the gas collecting chamber B. In such a structure part of the weight of the load member D is supported by its own submersion in the liquid on which the cover floats, and the remainder of the weight of the load member is supported by "extra" submersion of the deck portion C. Said deck portion would normally sink in the liquid only as much as required by its own weight. However, the load member causes said deck portion to sink an "extra" amount. It is this "extra" submersion above referred to.

2

In the form of our invention herein illustrated which is particularly adapted for use in tanks of relatively great diameter, the central portion of the cover is formed by a rigid, circular pontoon E of any preferred construction, provided with an annular rim 1, to the lower edge of which the flexible deck portion C is rigidly attached. The gas collecting chamber B is formed by a vertically-disposed, tubular member 2 at the center of the pontoon E, closed at its upper end by a gas-tight closure 3 and having its lower end open, so as to permit the gases on the underside of the cover to flow freely into the gas collecting chamber. Gases are conducted from the chamber B to the atmosphere, or to a point where they are used, by an eduction pipe 4 leading away from said chamber. At the outer edge of the deck portion C there is a single relatively high or deep, annular, steel rim F, which is connected to the lateral edge of said deck portion by a liquid-tight joint, said rim being provided at its upper end with a flange 5. In addition to imparting stiffness to the peripheral portion of the cover, said rim supports or carries the load member D and co-acts with same to produce a rigid, annular girder of relatively great weight, that is attached to the peripheral edge of the flexible deck portion C, and said rim F also effectively prevents any liquid in the tank from getting onto the top side of said deck portion. Preferably, said load member is cast or molded in situ around the outer side of the rim F and is permanently attached to same by devices on the exterior of said rim that are embedded in the concrete or other similar material of which the load member is constructed, during the operation of casting or molding said member. Thus, as shown in Figure 1, the rim F can be provided with anchoring devices 6 that are embedded in the side face of the load member contacted by the rim, and can also be provided with radially-disposed ties or hangers 7 extending downwardly and outwardly from the upper end portion of the rim and embedded in the top surface of the load member, said ties or hangers 7 taking up tension or compression stresses to which the load member is subjected, in addition to functioning as tie bars between the flanged upper portion of the rim F and the peripheral portion of the load member D. In casting or shaping the load member, the rim F constitutes one side wall of the form into which the concrete is poured, and the bottom and other side wall of said form are constructed in the usual manner from lumber or removable form sections that are dismantled after the concrete has set. By constructing the

peripheral portion of the floating cover in the manner above described, we effect a considerable saving in steel, as only a single annular steel member, to wit, the rim F, is combined with the molded or cast load member D.

When the cover is not floating on the sewage or other liquid in the tank of the apparatus, as shown in dotted lines, any suitable means may be used to support said cover. We have herein illustrated a supporting means for the central portion of the cover consisting of a supporting structure G located at the center of the tank and resting on the bottom of same, and a supporting means for the peripheral portion of the cover, composed of chains 8 fastened to the upper end of the side wall A of the tank and attached to the load member D by bars or rods 9 at the lower ends of said chains embedded in the load member. Rain water or the like that collects on the top side of the deck portion C can be conducted away from same in various ways, as, for example, by one or more drains 10, as shown in the drawing 1.

Having thus described our invention, what we claim and desire to secure by Letters Patent is:

1. An apparatus, comprising a tank that is adapted to hold a liquid or liquid-like substance that is being stored or processed, a floating cover for said tank comprising a gas collecting chamber at approximately the center of said cover having provision for permitting gases on the underside of the cover to flow into said chamber, a flexible deck portion extending radially from said gas collecting chamber, a single, annular-shaped metal rim projecting upwardly at the periphery of said deck portion and joined to the peripheral edge of same by a liquid-tight joint; and an annular-shaped load member constructed of concrete or the like, cast or molded in situ on the outer face of said rim and interlocked with same so as to maintain said deck portion in an inclined position sloping upwardly and inwardly towards the center of the roof, said load member being located outside of or beyond said rim, whereby part of the weight of said load member is supported by its own submersion in the liquid on which the cover floats.

2. An apparatus, comprising a tank that is adapted to hold a liquid or liquid-like substance that is being stored or processed, a floating cover for said tank comprising a gas collecting chamber at approximately the center of said cover having provision for permitting gases on the underside of the cover to flow into said chamber, a flexible deck

portion extending radially from said gas collecting chamber, an annular-shaped metal rim projecting upwardly from the peripheral edge of said deck portion, and an annular-shaped load member, constructed of concrete or the like, attached to the outer side of said rim so as to maintain said deck portion in such a position as to induce the flow of gases on the underside of the deck portion into said gas collecting chamber, said load member being located outside of or beyond said rim, whereby part of the weight of said load member is supported by its own submersion in the liquid on which the cover floats.

3. An apparatus, comprising a tank that is adapted to hold a liquid or liquid-like substance that is being stored or processed, a floating cover for said tank comprising a gas collecting chamber at approximately the center of said cover having provision for permitting gases on the underside of the cover to flow into said chamber, a flexible deck portion extending radially from said gas collecting chamber, an annular-shaped metal rim projecting upwardly from the peripheral edge of said deck portion, and a load member of concrete or the like combined with said rim, for maintaining said deck portion in an inclined position sloping upwardly and inwardly towards the center of the roof, said load member being disposed in such relationship with said rim that part of the weight of said load member is supported by its own submersion in the liquid on which the cover floats.

4. An apparatus of the kind described in claim 3, which includes inclined tie members extending downwardly and outwardly from the upper end portion of said rim and having their lower end portions embedded in said load member.

JOHN H. WIGGINS.
JOHN W. ALLEN.
